FISHING LURE

Lloyd B. Shroff, Clay Township,
St. Joseph County, Ind.

Application November 23, 1949, Serial No. 6,215

Term of patent 3½ years

(Cl. D31—4)

To all whom it may concern:

Be it known that I, Lloyd B. Shroff, a citizen of the United States, residing in Clay township, in the county of St. Joseph, State of Indiana, have invented a new, original, and ornamental Design for a Fishing Lure, of which the following is a specification, reference being had to the accompanying drawing, forming part thereof.

Fig. 1 is a face view of a fishing lure embodying my new design.

Fig. 2 is an edge view of the lure as seen when viewed from the right in Fig. 1.

Fig. 3 is a face view of the lure showing the face opposite that illustrated in Fig. 1.

The characteristic features of my design reside in the portion shown in full lines.

I claim:

The ornamental design for a fishing lure, as shown and described.

LLOYD B. SHROFF.
